ADJUSTABLE TRANSMISSION LINE

Sidney B. Pickles, Jackson Heights, N. Y., assignor
to Federal Telephone and Radio Corporation,
a corporation of Delaware

Application May 12, 1942, Serial No. 442,657

16 Claims. (Cl. 178—44)

1

This invention relates to transmission lines and more particularly to a phasing unit therefor by which the effective length of an electrical line can be varied.

In the type of phasing unit heretofore commonly used, the lines were telescopingly coupled and phase adjustment made by trombone action. This type of phasing unit, however, is objectionable because it is clumsy and awkward to use and the adjustment is not smooth. Further, the differences in diameter of the cooperating telescoping parts of this type of unit effect discontinuities in the surge impedance so that reflections occur.

Bearing in mind the aforementioned disadvantages of the trombone type of phasing unit, it is an object of this invention to produce a phasing unit for electrical lines which is compact, easily operated, and in which the operating effect is smooth.

Another object of the invention is to produce a phasing unit incorporating electrical line segments of substantially constant surge impedance.

The above and other objects of this invention may be accomplished by oppositely disposing stationary arcuate segments of conductor material, one end of each segment having means for connection to an electrical line, and locating rotatable conductor means between the stationary segments for sliding engagement therebetween, so that upon rotation of the conductor means, the effective length of the electrical line is varied.

More particularly, the arcuate segments may be disposed in oppositely opposed pairs about a given axis and a movable member mounted for rotation about the given axis to movably support conductors extending crosswise between the oppositely opposed segments. The ends of the movable conductors have brushes, each of which conductively engages one of the arcuate segments. Thus, by rotation of the supporting member, the brushes of the movable conductors are moved along the arcuate segments thereby increasing or decreasing, as the case may be, the lengths of the electrical lines.

The arcuate segments may be suitably shielded by a casing which has a cylindrical portion extending adjacent and in spaced relation to the segments. Likewise, the movable conductors are provided with a shield disposed in a like spaced relation adjacent thereto.

In order to minimize the influence of portions of the arcuate segments extending beyond the points at which the conductor means engage the segments, the free ends of the arcuate segments are shorted or grounded to the shield. In addi-

2

tion to shorting the free ends of the segments, a movable arm may be carried by the rotating member and provided with brushes to short the adjacent arcuate segments at a given distance from the brushes of the movable conductor means. The arm may be made adjustable relative to the supporting member so that the shorting effect thereof can be adjusted for a distance from the point of conductor engagement with the segments equal to substantially one-fourth of the wave length of the current carried by the electrical lines. This movable short gives an open effect to the free ends and insures against the otherwise free end portions of the segments producing reflections or influencing the phasing effect of the unit. Thus, as the effective lengths of the electrical lines are changed by manipulation of the rotary member, the movable shorting arm is moved therewith so as to short the arcuate segments at substantially one-fourth wave length of the current carried by the lines and thereby eliminate any reflections or phasing effect that the terminal end portions of the segments might otherwise impose upon the lines.

25. This invention may be applied to coaxial cables as well as plural line installations. In the case of coaxial cables the free end portions of the segments are shorted to the casing or shield of the unit in substantially the same manner as hereinbefore described. That is to say, the free or terminal ends of the segments are conductively connected to the casing and movable shorting brushes are disposed between the segments and the shield for movement one-fourth of a wave length beyond the brushes of the movable conductor.

For a better understanding of the invention, reference may be had to the following detailed description to be read in connection with the drawings, in which

Fig. 1 is a plan view of one embodiment of this invention, with the top portion thereof removed;

Fig. 2 is a vertical cross-sectional view taken along line 2—2 of Fig. 1;

Fig. 3 is a cross-sectional view taken along line 3—3 of Fig. 2;

Fig. 4 is a vertical cross-sectional view taken along line 4—4 of Fig. 1; and

Fig. 5 is a schematic view of another embodiment of the invention.

Referring to Figs. 1, 2, 3 and 4 of the drawings, the embodiment of the invention therein illustrated comprises a cylindrical casing or shield 10 having top and bottom portions 12 and 14 respectively. The top portion 12 has secured thereto

a boss 16 and the bottom portion 14 has secured thereto a boss 18. Supported in the bosses 16 and 18 are stub shafts 20 and 21 respectively, to which diametrically-extending arms 22 and 23 are adjustably secured by suitable clamps 24 having tightening elements 26. These arms 22 and 23 are joined at both ends by cross-straps 61 integral therewith, thus forming a generally rectangular frame whose purpose is hereinafter explained. An inner shield 30 of flat rectangular form is provided with supporting extensions 32 and 34 integral thereto and extending at right angles as shown in Fig. 3. The upper supporting extension 32 is received over the stub shaft 20 and the lower extension 34 is received on the stub shaft 21. The extension 32 is clamped between the arm 22 and a flanged sleeve 35 carried by the shaft 20. The extension 34 is likewise clamped between the arm 23 and a flanged sleeve 36.

Mounted in spaced relation to the cylindrical shield 10 are two pairs of oppositely disposed arcuate conductor segments 40, 42 and 41, 43. As shown in Fig. 1, each arcuate segment is supported at one end by a metallic block 44 thereby grounding that end of the segment to the shield 10. At suitably spaced intervals, each segment may be further supported by insulators 46 to maintain it in properly spaced relation to the shield. To avoid altering the size and cross-section of the conductors, the insulators 46 are secured thereto by screws 47 the flat heads of which are soldered to the surfaces of the conductors. The end of each segment opposite the end grounded to the shield 10 is suitably connected to a lead of a cable 48 or 49 to which a transmission or other electrical line may be connected.

The two shields 10 and 30 are preferably made of the same material and have substantially the same thickness.

Mounted on the inner shield 30 by insulator blocks 50 and 51, are two conductors 52 and 53. The conductors 52 and 53 are of the same material and have the same shape and cross-sectional area therealong as the arcuate segments, and are spaced the same distance from the shield 30 as the arcuate segments are spaced from the shield 10. The mountings 50 (Fig. 3) between the conductors 52, 53 and the insulators 50, 51 are the same as the insulated supporting mounts for the arcuate segments (Fig. 2). The conductors 52 and 53 are straight and extend along the diameter of the circle which includes the arcuate segments. The ends of the conductors 52 and 53 are provided with brushes 56, 56' and 57, 57' respectively for resilient engagement with the arcuate segments. As shown in Figs. 1 and 2, the brushes 56, 56' of the conductor 52 are in engagement with the segments 40 and 41 and the brushes 57 of the conductor 53 are in engagement with the segments 42 and 43.

The shaft 20 is provided with a suitable handle 60 so that the shaft 20, the associated shield 30 and the conductors 52, 53 may be readily rotated in either direction by manipulation of the handle. By turning the handle to the right or left as desired, the effective length of the composite transmission line formed by conductors 52 and 53 and the active portions of the arcuate segments may be lengthened or shortened, as the case may be. This composite line may be considered as consisting of a first section of line comprising the active portion of the pair of segments 40 and 42 (i. e. the portion shown between cable 48 and brush 56 in Fig. 1) connected to a second section of line comprising the whole of

conductors 52 and 53, this being in turn connected to a third section of line comprising the active portion of the pair of segments 41 and 43 (i. e. the portion shown between brush 56' and cable 49 in Fig. 1). The lengths of the first and third of these sections (and hence the length of the composite line formed of all three sections) is varied by turning handle 60.

The unused or free end portions of the arcuate segments constitute unwanted stub line sections similar to building-out sections bridged across the above described composite line at the points where the first and third sections join the second section. If these stub sections were not controlled they might have such length as to present low or fairly low impedances to the composite line thus causing large or fairly large reflections.

For the purpose of preventing the unused or free end portions of the arcuate segments from acting as substantial impedances shunted across this line, and thus causing reflections, the cross traps 61 of arms 22 and 23 are provided with brushes 62 and 64 (Fig. 3) each of which is adapted to engage a pair of the arcuate segments of the two pairs 40, 42 and 41, 43. As shown, the brush 62 engages segments 41 and 43 while the brush 64 engages both of the segments 40 and 42 thereby shorting the segments. The distance of the shorting brushes 62 and 64 from the conductive engagement of the segments by the conductors 52, 53 may be changed depending upon the frequency of the current carried by the transmission line. This adjustment, as hereinbefore suggested, may be made by loosening the elements 26 and moving the arms 22, 23 to the desired angular relation with respect to the conductors 52, 53. The distance between the brushes 62, 64 and the brushes 56, 56', 57, 57' as measured along the segments, is preferably selected as one-fourth of the wave length of the frequency of the current of the transmission line. This relation effectively renders practically infinite the bridged impedances constituted by the unused or dead-end portions of the arcuate segments.

From the foregoing, it will be readily apparent that the effective length of the composite electrical line may be readily and easily changed by simple manipulation of the handle 60. For each rotary movement of the handle, the position of the conductors 52, 53 will be changed so that the effective length of the line will be varied accordingly. Simultaneously with this movement, the arms 22 and 23 will move to maintain a shorting connection between adjacent arcuate segments at a distance substantially one-fourth wave length beyond the location of the brushes 56, 57 of the movable conductors.

The provision of the inner shield 30 adjacent the movable conductors 52, 53 insures the maintenance of a surge impedance for these conductors which corresponds to the surge impedance of the arcuate segments with their shield 10. This uniformity of surge impedance along the composite line together with the elimination of any substantial bridged impedances due to the unused or free ends results in avoiding reflections to a greater degree than any known type of adjustable length line.

For co-axial transmission lines, an embodiment slightly different from the one hereinbefore described may be provided. In this form, as shown in Fig. 5, only two single oppositely opposed arcuate segments 70 and 72 are necessary. These segments are suitably supported in spaced relation on a casing 71 by insulating

blocks 73. One end of each segment is connected to the inner conductors 74 of two cable sections while the casing is connected to the outer portions 75 of the coaxial cable. The other ends of the segments are shorted by conductive connection to the casing by metallic blocks 76.

Any suitable rotary member 77 may be mounted on the casing to movably support a conductor 78. This conductor is provided with brushes 79 for conductive engagement with the two segments. By turning the rotary member, the effective length of the composite line interconnecting the two inner conductors 74 may be varied.

The rotary member 77 may also be provided with arms 80 and 81 each having brushes 83 and 84 for sliding engagement with one of the segments and the casing respectively. The location of the arms 80, 81 with respect to the conductor 78 may be adjustably determined so that the shorting effect of the brushes 83, 84 results at a distance from the brushes 79 equal to substantially one-fourth the wavelength of the current carried by the conductor.

As described in connection with the first embodiment, a shield 85 having brushes 86 for conductive engagement with the casing 71 is provided for movement, the spacing of conductor 78 therefrom being the same as the spacing of segments 70, 72 from the casing 71. This spacing may be less than the spacing between inner and outer conductors of the high frequency coaxial cables 75 in order to yield the same surge impedance as that of the cables. Alternatively the conductors 70, 72 and 78 may be of larger diameter than conductors 74 or may be of flat cross-section so as to yield with one-sided shielding the same surge impedance as the conductors 74 which are shielded on all sides.

While two embodiments of the invention have been shown and described, it will be readily apparent to those skilled in the art that many changes, variations and adaptations thereof are possible without departing from the invention. It will be understood, therefore, that the foregoing illustration and description is to be regarded as illustrative of the invention only and not as a restriction upon the appended claims.

What is claimed is:

1. A phasing unit comprising stationary arcuate segments of conductor material, a shield disposed adjacent said segments and forming therewith a length of line having a predetermined surge impedance, a rotatable member, conductor means movable with said member and having sliding engagement with said segments, and a second shield disposed adjacent said conductor means and rotatable with said member said second shield forming with said conductor means a length of line having a surge impedance substantially equal to said first mentioned surge impedance.

2. A phasing unit comprising stationary arcuate segments of conductor material, one end of each segment being connectable to an electrical line having a given surge impedance, a shield disposed adjacent said segments and forming therewith a length of line having substantially the same surge impedance as the surge impedance of said electrical line, a rotatable member, conductor means movable with said member and having sliding engagement with said segments, and means to short the other ends of said segments to said shield.

3. A phasing unit comprising stationary ar-

cuate segments of conductor material, a shield disposed adjacent said segments, a rotatable member, conductor means movable with said member and having sliding engagement with said segments, means movable with said member to short said segments to said shield at a distance from the points of sliding engagement by said conductor means, and said distance being equal to a portion of the wavelength of the current carried by said lines.

4. A phasing unit comprising stationary arcuate segments of conductor material, one end of each segment being connectable to an electrical line, a shield disposed adjacent said segments, a rotatable member, conductor means movable with said member and having sliding engagement with said segments, means to conductively connect the other ends of said segments to said shield, means movable with said member to short said segments to said shield, means to maintain the shorting means at a distance from the points of the sliding engagement of said conductor means, and said distance being equal to substantially one-fourth the wavelength of the current carried by the electrical lines.

5. A phasing unit comprising stationary arcuate segments of conductor material, a shield disposed adjacent said segments, a rotatable member, conductor means movable with said member and having sliding engagement with said segments, means movable with said member to short said segments to said shield, and means for adjusting the angular relation between the shorting means and said conductor means so that the distance between the shorting means and the points of said sliding engagement may be changed for currents of different frequencies.

6. A phasing unit comprising two pairs of stationary arcuate segments of conductor material in oppositely disposed co-axial relation, means at one end of each segment to connect the segment to an electrical line, the other ends of the adjacent segments of the two pairs being connected together, a rotatable member co-axial with said segments, and conductors rotatable with said member, each of said conductors extending radially in opposite directions from said member and being so disposed as to provide conduction between one segment of each of said pairs.

7. A phasing unit comprising two adjacent pairs of oppositely disposed stationary arcuate segments of conductor material, a rotatable member, conductors movable with said member, each conductor being so disposed as to provide conduction between the segments of one of said pairs, means movable with said member and slidably engaging the adjacent segments of the two pairs at a distance beyond the points of conduction between said conductors and said segments, and said distance being a predetermined portion of the wavelength of the current carried by the segments.

8. A phasing unit comprising two adjacent pairs of oppositely disposed stationary arcuate segments of conductor material, a rotatable member, conductors movable with said member, each conductor being so disposed as to provide conduction between the segments of one of said pairs, means for shorting the segments of the adjacent pairs, and means to adjust the location of the shorting means relative to said conductors.

9. A phasing unit comprising two adjacent sets of segments each set comprising two oppositely disposed stationary arcuate segments of con-

ductor material, a shield disposed adjacent the segments of said sets, one end of each segment being connectable to an electrical line, the other ends of the adjacent segments being connected together, a movable member, conductors movable with said member, each conductor being so disposed as to provide conduction between the two opposite segments of one of said sets, and a second shield disposed adjacent said conductors and movable with said member.

10. The phasing unit defined in claim 9 characterized by the fact that, the spacing between the first-mentioned shield and said segments, and the spacing between said second shield and said conductors are substantially the same.

11. A phasing unit comprising two adjacent sets of segments each set comprising two oppositely disposed stationary arcuate segments of conductor material, means at one end of each segment to connect the segment to an electrical line, a shield disposed adjacent said segments, means conductively connecting the other ends of the segments of said sets together, a movable member, conductors movable with said member, each conductor being so disposed as to provide conduction between the two opposite segments of one of said sets, and a shield disposed adjacent said conductors.

12. A phasing unit comprising two adjacent sets of segments each set comprising two oppositely disposed stationary arcuate segments of conductor material, means at one end of each segment to connect the segment to a transmission line, a shield disposed adjacent said segments, means conductively connecting the other ends of the segments of said sets together, a movable member, conductors movable with said member, each conductor being so disposed as to provide conduction between the segments of one of said sets, a shield disposed adjacent said conductors, and means movable with said member and slidably engaging the adjacent segments of the two sets at a distance beyond the points of conduction between said conductors and said segments, and said distance being substantially equal to one-fourth of the wave-length of the current carried by the segments.

13. A phasing unit comprising a cylindrical casing, at least two arcuate segments, means to support the segments in spaced relation to said

5 casing, one end of each segment being conductively connected to said casing, a member, means to rotatably support said member coaxially of said casing, a conductor carried by said member and having sliding engagement with said two segments, and an arm connected to said member having sliding engagement with said segments to electrically connect the segments at a distance beyond the sliding engagement between said conductor and said segments.

10 14. A phasing unit comprising a cylindrical casing, two adjacent sets of segments each set comprising two oppositely disposed arcuate segments supported in spaced relation to said casing, 15 said casing having top and bottom portions, each of said portions having a stub shaft rotatably mounted therein, the shafts being coaxial, a piece of sheet material supported by the stub shafts, a portion of said piece being disposed in a plane parallel to the axis of the stub shafts, conductors, insulated means to support said conductors in spaced relation to said sheet material, brushes on the ends of said conductor for sliding engagement with said segments, and an arm adjustably supported on one of the shafts and having sliding engagement with adjacent segments of the two sets to electrically connect the segments at a distance beyond the sliding engagement between said conductor and said segments equal to a predetermined fraction of the wavelength of the current carried by said segments.

20 15. A phasing unit for adjusting the electrical length of a transmission line comprising line section extensions, one end of each section being adapted for connection to part of said line, the other ends of said extensions being free, conductive connecting means therefor adjustable along the lengths of said extensions, conductive shields in parallel relation with said extensions and with said connecting means and co-operating therewith to constitute lines whose surge impedance simulates the surge impedance of the line being adjusted.

25 16. A phasing unit according to claim 15, including means under the control of the adjustable connecting means for preventing the free ends of the line extensions from affecting the impedance of the transmission line under adjustment.

SIDNEY B. PICKLES.
